PANEL.

No. 16,229.

Patented Sept. 8, 1885.

UNITED STATES PATENT OFFICE.

FREDERICK MANKEY, OF WILLIAMSPORT, PENNSYLVANIA.

DESIGN FOR A PANEL.

SPECIFICATION forming part of Design No. 16,229, dated September 8, 1885.

Application filed July 18, 1885. Term of patent 7 years.

To all whom it may concern:

Be it known that I, FREDERICK MANKEY, of Williamsport, Lycoming county, Pennsylvania, have invented and produced a new and original Design for Panels, of which the following is a specification, reference being had to the accompanying photograph, forming part hereof.

My design is intended for an ornamental panel for doors, wainscots, &c.; and it consists of the central figure, A, flower-shaped, as shown, a surrounding rectangular flat space, B, and a series of pyramidal elevations, C, arranged to form a rectangular frame surrounding the space B. The aforesaid parts of my design are formed upon the frusto-pyramidal

elevation D. At the corners of the panel are four pyramids, E, and between said pyramids are elongated pyramidal elevations F. Between the elevations D, E, and F are channels or spaces G H I J.

I claim—

The design for a panel, substantially as herein shown and described, consisting of the central figure, A, rectangular space B, pyramidal elevations C, E, and F, frusto-pyramidal elevation D, and channels or spaces G H I J. 25

FREDERICK MANKEY.
